UNITED STATES PATENT OFFICE.

ROBERT B. CHITTENDEN, OF GLENS FALLS, NEW YORK.

READING STAND.

Application filed May 23, 1922. Serial No. 563,067.

The object of the invention is to provide a reading stand or rack particularly adapted for invalid use in connection with a bed or chair as a means of supporting books, newspapers and the like within convenient range of the vision of the patient and particularly to provide a device of this type of which the rack proper or supporting member may readily be extended or contracted in area to suit the size of the article which is to be supported thereby while permitting of folding into relatively compact form when not in use; and with this object in view the invention consists in a construction and combination of parts of which a preferred embodiment is shown in the accompanying drawings, wherein:

Figure 1 is a view of a stand embodying the invention with the rack member thereof in the extended or expanded condition.

Figure 2 is a similar view showing the rack member in its contracted or folded condition.

Figures 3 and 4 are sectional views respectively on the planes indicated by the lines 3-3 and 4-4 of Figure 1.

Figures 5 and 6 are sectional views respectively on the planes indicated by the lines 5-5 and 6-6 of Figure 2.

The stand consists essentially of a foldable rack member 10 supported from a suitable base 11 by a standard 12—the base preferably being supported for movement with facility over the surface of the floor as for example by being provided with castors 13, and the upright being arranged to rise from one end of the base so that the latter may extend under the chair or bed adjacent to which the stand is being used, to project beneath the rack member and thus prevent the tilting thereof. The upright or standard preferably is of extensible construction consisting for example of the tubular lower member 14 into which fits the rod member 15 held at the desired adjustment by a thumb screw 16. Also the rack member which comprises a main section or element 17 and supplemental sections 18, 19 and 20, is provided at one side of the main section or element with a pivot pin 21 fitted in a socket 22 in the end of the horizontal arm 23 of the upright to provide for tilting or arranging the rack member at the desired inclination. The rack member is

locked in the desired position by means of a thumb screw 24.

The main element or section of the rack member is provided with forwardly directed guides 17^a which receive the marginal bars 18^a of the supplemental element or section 18 to provide for the lateral sliding of the side member 18 into a position substantially in coextending relation with the main element or section, and correspondingly the section 20 is provided with guide 20^a for receiving the upper marginal bar of the section 19 for relative lateral sliding movement, and the main element or section 17 and the section 18 are further provided with guides 17^b and 17^c to receive the collapsed members 20 and 19, so that the supplemental sections 18, 19 and 20 may be folded into positions in substantial parallelism with the main section 17 as shown in Figure 2, to contract the rack member substantially to the dimensions of the section or element 17 when a book or comparatively small object is to be supported thereby. The upper supplemental sections 19 and 20 carry yielding fingers 25 extended obliquely across the face thereof for clamping a paper or like object in place on the rack member and these fingers when the supplemental sections are in the collapsed or folded position occupy a corresponding relation with the main section or element 17 for a corresponding purpose. The intermediate cross bars 26 and 27 of the sections 19 and 20 are disposed in telescoping relation and are slidably mounted upon the side bars of said sections by means of pins 28 engaging slots 29, to permit of the movement thereof to the upper ends of the sections 19 and 20 when the latter are slid downwardly in rear of the main section or element 17. For holding the upper supplemental sections or elements in their extended positions there is employed a latch 30 mounted upon one of the side bars of the main section or member and having a pin 31 for engagement with a socket in the corresponding side bar of the section 20. The section 18 is mounted to guide on the section 17 due to the interengaging guide bars 17^a and 18^a, while the sections 20 and 19 may collapse in parallelism relative to the sections 17 and 18 due to the guides 17^b and 17^c carried by the sections 17 and 18, as shown clearly in Figures 1, 3, 5 and 6. When the section 18 is collapsed behind the section 17, the sec-

tions 20 and 19 may be moved to closed positions in the guides 17^b and 17^c, in which case the section 19 will move to a position behind the section 20. As previously stated, the bars 26 and 27 telescope, as shown in Figure 3, although the bars are angular in cross section. The pins 28 which are carried by the bar 27 project from the exterior of the bar 27 and are headed in order to be retained in the slots 29 of the left hand upright bar of the section 20. The pin 28 which is carried by the bar 26 (which telescopes the bar 27) projects from the rear face of the bar 26 at one end thereof and is headed in order to be retained in the slot 29 of the left hand perpendicular bar of the section 19. Obviously, when the sections 20 and 19 are collapsed while the section 18 remains extended, if it be desired to use the frame in this manner, the bars 26 and 27 may move upwardly, the pins 28 moving in the slots 29. The pins 28 assist in retaining all the sections connected while the for-

wardly extending flange of the bar 18^a overlies the bar 17^a of the section 17 and further assists in retaining the sections connected. The guide 20^a at the top of the section 20 also acts to retain the sections connected, particularly the sections 20 and 19.

Having described the invention, what is claimed as new and useful is:—

A device for the purpose indicated comprising a rack member embodying main and supplemental elements of which the former is provided with guides receiving marginal bars of the latter to provide for lateral sliding movement of the same in a position substantially in coextending relation with the main element, both the main and supplemental elements having sections slidably mounted upon them for movement in coextensive relation to extend or reduce the area of the rack member vertically.

In testimony whereof he affixes his signature.

ROBERT B. CHITTENDEN.
